COLOR STABILIZATION OF ORTHO-BENZYL PARACHLOROPHENOL

Frederic J. Shelton, Tacoma, Wash., assignor to Reichhold Chemicals, Inc., White Plains, N.Y.
Filed Oct. 29, 1968, Ser. No. 771,594
Int. Cl. C07c 37/22

U.S. CL. 260—619 R

1 Claim

ABSTRACT OF THE DISCLOSURE

This invention discloses a composition, comprising ortho-benzyl parachlorophenol and a color stabilizer therefor. This color stabilizer includes from about 0.01% to about 0.5% thiourea and from about 0.025% to about 0.75% of an organic phosphite by weight, based upon ortho-benzyl parachlorophenol.

This invention relates to the stabilization of the color of ortho-benzyl parachlorophenol and its solutions in isopropanol.

The stabilization of color in phenolic compounds has been a problem of long standing. It has been a particular problem to stabilize the color of ortho-benzyl parachlorophenol. Solid ortho-benzyl para-chlorophenol or alcoholic solutions of ortho-benzyl para-chlorophenol when subjected to light tend to darken in color. The color developed is dependent upon the types of trace ions present and ranges from rose-pink to dark brown. Unprotected ortho-benzyl parachlorophenol, when subjected to light will show a marked darkening in color in a matter of only a few days exposure to light.

In the quest to find a satisfactory color stabilizer for ortho-benzyl parachlorophenol, many compounds were tried which act as color stabilizers for other organics and it was found that for one reason or another they were unsatisfactory. Either they did not stabilize the color, or the quantity required to achieve color stabilization was far greater than could be tolerated as a minor constituent in technical grade ortho-benzyl parachlorophenol.

The uses for ortho-benzyl para-chlorophenol are many and varied. One major industrial use is as an ingredient for household germicides. Such household germicide formulations are in many cases sold on the basis of each manufacturer having his own distinctive color. It is therefore exceedingly important that the ortho-benzyl parachlorophenol should not change color and thereby change the color of the final formulation.

Ortho-benzyl parachlorophenol is also used as dyeing assistant and in such an application it is vitally important that the ortho-benzyl parachlorophenol does not produce the color shift.

It is therefore an object of this invention to provide a stabilizer for ortho-benzyl para-chlorophenol which prevents the darkening in color on prolonged standing.

Another object of this invention is to provide a stabilizer for ortho-benzyl para-chlorophenol which prevents the darkening in color on exposure to light.

A further object of this invention is to provide a stabilizer for alcoholic solutions of ortho-benzyl parachlorophenol which prevents darkening in color on exposure to light and prolonged standing.

Additional and further objects and advantages of this invention will be set forth in part in the description that follows and in part will be obvious therefrom or may be learned by practice of this invention, said objects being realized and attained by means of the steps, methods, compositions, combinations and improvements pointed out in the appended claims.

2

To achieve the foregoing objects and in accordance with its purpose as embodied and broadly described, the process of this invention comprises the addition of a combination of thiourea and an organic phosphite to stabilize ortho-benzyl parachlorophenol. Said ortho-benzyl parachlorophenol could be in a solid state or it could be dissolved in a solvent e.g. isopropyl alcohol. The above mentioned components are only slightly effective when used individually. However, when combined in proper ratio a very effective stabilization is produced. Thus the original snow-white color of solid ortho-benzyl parachlorophenol or the very light straw yellow color of alcoholic solutions of ortho-benzyl parachlorophenol can be preserved even on prolonged exposure to bright light.

10 The use of from about 0.025% to about 0.75% of organic phosphites in combination with an amount of thiourea ranging from about 0.01% to about 0.1% was found to impart a very satisfactory degree of color stabilization. The percentages are expressed in weight percent and are 20 based on the amounts of ortho-benzyl parachlorophenol used.

While organic phosphites have been suggested in the past as color stabilizers for plastic resins and are described for instance in U.S. Pat. 2,564,646 and 2,716,092, nothing 25 has been made known heretofore as to the use of such phosphites in combination with thiourea.

The organic phosphites which are suitable in the stabilizer composition of the present invention are selected from the class consisting of substituted or unsubstituted 30 aliphatic or aromatic phosphites, containing both alkyl, aryl and alkaryl groups, organohalophosphites and phosphorus halides containing one or two substituted or unsubstituted alkoxy and/or aryloxy groups bonded to the phosphorus atom. These phosphites include trioctyl phosphite, tris (2-chloroethyl) phosphite, tridecyl phosphite, phosphite ester derivatives of glycols, polyethylene glycols and glycol ethers like tris-dipropylene glycol phosphite and 2,4,6 trichlorophenyl bis-dipropylene glycol phosphite, etc., triphenyl phosphite, tri-(o-xenyl) phosphite, di-(p-tert-butylphenyl) monophenyl phosphite, diphenyl-mono-ortho-chlorophenyl phosphite, di-(nonylphenyl)-mono-2-chloroethyl phosphite, phenyl-di-(α -chloropropyl) phosphite, di-nonyl- β -chloropropyl-phosphite, diphenoxychlorophosphorus, octylphenoxydichlorophosphorus, di-(nonylphenoxy) dichlorophosphorus, phenoxyoctyloxychlorophosphorus, and the like. The preferred phosphite however is the tri-phenylphosphite on account of the outstanding results achieved therefrom.

50 The accompanying drawing serves to illustrate the synergistic effect of a typical combination of 0.05% thiourea and 0.1% triphenylphosphite, when compared with the corresponding effect activated by the use of 0.05% thiourea alone and 0.1% triphenylphosphite alone.

55 This invention will be further illustrated by description in connection with the following specific examples of the practice of it. The Examples I and II serve solely to show the effect of exposure to light of a conventional orthobenzyl parachlorophenol, which has not been color 60 stabilized.

EXAMPLE I

Solid ortho-benzyl parachlorophenol having a freezing point of 49.6° C. and containing 99.9% ortho-benzyl parachlorophenol by infra-red analysis was exposed to north light in a clear glass container. The original material was nearly snow-white in color. After two days' exposure, a very distinct pink coloration developed. After one week's exposure, the material was light reddish-brown. After one month's exposure, it was medium brown and after three month's exposure, it had become dark brown in color.

3
EXAMPLE II

A portion of the same stock of ortho-benzyl parachlorophenol was used to prepare a 75.0% solution of ortho-benzyl parachlorophenol in isopropanol. The solution was exposed under the same north light conditions as Example I. The solution was originally very light straw-yellow in color. After one week's exposure, the color was bright yellow. After one month's exposure, the color had become a yellow-brown and after six-months' exposure, was a strong dark brown color. These colors were expressed in accordance with the Gardner 1953 series as follows:

Days:	Color
0	1
2	6
7	9
30	15
90	18

EXAMPLE III

A portion of the stock of ortho-benzyl parachlorophenol used in Example I was melted and divided into thirteen equal portions. Each molten portion was treated with a different level of thiourea and then flaked on a stainless steel plate. The flaked samples were then exposed under the same north light conditions as Example I. The quantities of thiourea added and the color changes noted over a ninety-day period are shown below:

COLOR					
Thiourea, weight percent	Days				
	0	2	7	30	90
0.000	White	Yellow	Pink	Purple-brown	Purple-brown
0.010	do	White	do	do	Pink
0.025	do	do	Yellow	Ivory	Ivory
0.050	do	do	White	Ivory	White
0.075	do	do	do	do	Do.
0.100	do	do	Yellow	Pink	Do.
0.125	do	do	do	do	Do.
0.150	do	do	do	do	Do.
0.175	do	do	do	do	Light yellow.
0.200	do	do	do	do	Yellow.

EXAMPLE IV

The same procedure was used as in Example III except that triphenyl phosphite was used as the treating agent. The quantities of triphenyl phosphite and the color changes as noted over a ninety-day period are shown below:

COLOR					
Triphenyl phosphite, weight percent	Days				
	0	2	7	30	90
0.000	White	Yellow	Buff	Brown	Brown
0.010	do	White	do	do	Do.
0.025	do	do	Yellow	do	Do.
0.050	do	do	White	do	Do.
0.075	do	do	do	Buff	Do.
0.100	do	do	do	do	Do.
0.250	do	do	do	do	Do.
0.500	do	do	do	Tan	Do.
0.750	do	do	do	Tan	Buff
1.000	do	do	do	Ivory	Tan
1.250	do	do	do	do	Tan
1.500	do	do	do	White	Do.
1.750	do	do	do	Ivory	Do.
2.000	do	do	do	do	Do.

EXAMPLE V

The same procedure was used as in Example III except that 0.050 weight percent thiourea was added to all samples and triphenyl phosphite was added in the amounts

shown below. The color changes noted over a ninety-day period were as follows:

5	0.050% thiourea plus triphenyl phosphite weight percent	COLOR				
		0	2	7	30	90
0.000	White	White	Pink	Purple-brown	Purple-brown	
0.010	do	do	do	Pink	Pink	
0.025	do	do	Ivory	Ivory	Ivory	
0.050	do	do	White	White	White	
0.075	do	do	do	do	Do.	
0.100	do	do	do	do	Do.	
0.250	do	do	do	do	Do.	
0.500	do	do	do	do	Do.	
0.750	do	do	do	do	Do.	
1.000	do	do	do	do	Ivory	
1.250	do	do	do	do	Do.	
1.500	do	do	do	do	Do.	
1.750	do	do	do	do	Light yellow.	
2.000	do	do	do	do	Yellow.	

EXAMPLE VI

A portion of the stock of solid ortho-benzyl parachlorophenol used in Example I was used to prepare a 75% ortho-benzyl parachlorophenol, 25% isopropanol solution. To samples of this solution thiourea was added in the amounts shown below. Samples were exposed to the same light conditions as in Example I and color changes as noted over a 90-day period were as follows:

30	Thiourea, weight percent	COLOR *				
		0	2	7	30	90
0.000	1	2	10	16	18	
0.010	1	2	9	16	18+	
0.025	1	2	9	16	18+	
0.050	1	2	8	16	18+	
0.075	1	2	6	16	17	
0.100	1	1	5	13	15	

* The color is expressed as Gardner 1953 series.

EXAMPLE VII

45 The same procedure and ingredients were used as in Example VI except that triphenyl phosphite was used in place of thiourea. Quantities added and color changes noted over a ninety-day period are recorded below:

50	Triphenyl phosphite, weight percent	COLOR *				
		0	2	7	30	90
0.000	1	2	9	16	18	
0.010	1	2	6	13	16	
0.025	1	2	6	13	16	
0.050	1	2	6	13	16	
0.075	1	2	6	13	16	
0.100	1	2	6	13	16	
0.250	1	2	6	13	16	
0.500	1	2	6	13	16	
0.750	1	2	6	13	16	
1.000	1	2	6	13	11	
1.250	1	2	6	13	16	
1.500	1	2	6	13	16	
1.750	1	2	6	13	16	
2.000	1	2	6	13	16	

* The color is expressed as Gardner 1953 series.

EXAMPLE VIII

The same procedure and ingredients were used as in Example VI except that 0.050 weight percent thiourea based upon the contained ortho-benzyl parachlorophenol was added to all samples. Additionally triphenyl phos-

phite in the amounts shown below were added. The color changes taking place over a ninety-day period were as follows:

0.050% thiourea plus triphenyl phosphite, weight percent	COLOR *				
	0	2	7	30	90
0.000-----	1	2	8	16	18+
0.010-----	1	2	6	9	14
0.025-----	1	1	3	6	10
0.050-----	1	1	1	2	4
0.075-----	1	1	1	1	1
0.100-----	1	1	1	1	1
0.250-----	1	1	1	1	1
0.500-----	1	1	1	1	1
0.750-----	1	1	1	1	1
1.000-----	1	1	1	1	1
1.250-----	1	1	1	1	2
1.500-----	1	1	1	1	2
1.750-----	1	1	1	2	3
2.000-----	1	2	2	3	4

* The color is expressed as Gardner 1953 series.

What is claimed is:

1. A composition comprising ortho-benzyl parachlorophenol and a color stabilizer therefor, said stabilizer consisting essentially of (a) about 0.05 thiourea and (b) about 0.05 triphenylphosphite, based upon the weight of said ortho-benzyl parachlorophenol.
